(57) **CLAIM**

The ornamental design for a lunch box, as shown and described.

DESCRIPTION

FIG. 1 is a perspective view of a lunch box showing my new design, shown in an open station;

FIG. 2 is a perspective view of the lunch box show in a closed position;

FIG. 3 is a front elevational view of the lunch box shown in FIG. 2;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the lunch box that form no part of the claimed design.
